UNITED STATES PATENT OFFICE

163,171

COMBINATION QUESTION MACHINE AND NAPKIN DISPENSER

Fred E. Erickson and Loyal K. Roe, Sacramento,
Calif.; said Roe assignor to said Erickson

Application March 14, 1950, Serial No. 8,520

Term of patent 7 years

(Cl. D44—24)

To all whom it may concern:

Be it known that we, Fred E. Erickson and Loyal K. Roe, citizens of the United States, and both residents of the city and county of Sacramento, State of California, have invented a new, original, and ornamental Design for a Combination Question Machine and Napkin Dispenser, of which the following is a specification, reference being had to the accompanying drawing, forming part thereof.

Figure 1 is a front perspective view of a combination question machine and napkin dispenser, showing our new design; and

Figure 2 is a side elevational view thereof.

We claim:

The ornamental design for a combination question machine and napkin dispenser, substantially as shown.

FRED E. ERICKSON.
LOYAL K. ROE.
